UNITED STATES PATENT OFFICE.

RAYMOND ARMSTRONG, OF GRAND ISLAND, NEW YORK.

ANTISKID DEVICE.

1,282,359.

Specification of Letters Patent.

Patented Oct. 22, 1918.

Application filed June 6, 1918. Serial No. 238,545.

To all whom it may concern:

Be it known that I, RAYMOND ARMSTRONG, a citizen of the United States, residing at Grand Island, in the county of Erie and State of New York, have invented certain new and useful Improvements in Antiskid Devices, of which the following is a specification.

This invention is an anti-skid device and 10 has special reference to motor driven vehicles.

One object of this invention is the production of an anti-skid device which includes a source of sand supply, whereby sand may be 15 dispensed in front of the driving wheels of a motor vehicle for preventing the same from skidding or slipping, by the passing of sand in the path of movement thereof.

Another object of this invention is the production of an anti-skid device wherein a pair 20 of slides are connected to the sand reservoir, while operating means is connected to a foot lever, so that the chauffeur of the motor driven vehicle may swing the lever to shift 25 the slide and thus permit sand to be dispensed in the path of movement of the rear or driving wheels of the vehicle.

Broadly stated, the invention consists of a reservoir which has a curved bottom to cause 30 the sand therein to pass toward its ends, slides carried by guides adjacent the ends of the reservoir, boxes connected to the guides of the slides, pipes extending from said boxes, whereby when said slides are moved, 35 sand may pass from the reservoir through the slides and boxes and then into the pipes to be discharged in the path of movement of the rear wheels of the vehicle, rods connected to said slides, a plate connected to said rods, 40 an operating lever having a rod connected thereto and to said plate, whereby when the lever is shifted, said slides may be actuated.

One practical form of construction and assembly of the present invention will be hereinafter described and is illustrated in the accompanying drawing, in which—

Figure 1 is a side elevation of the anti-skid device, a portion of the same being broken away and the reservoir being shown 50 in section.

Fig. 2 is a top plan view of the reservoir, illustrating the manner in which the actuating rods are connected to the plates.

Fig. 3 is a section taken on the line 3—3 55 of Fig. 2, and

Fig. 4 is a detail perspective view of one of the slide plates.

In the preferred embodiment of the present invention about to be described, it will be seen that 5 indicates in general the floor 60 of the motor vehicle which has a slot 6 adjacent its forward end, while a depending bracket 7 is connected to the body and is contiguous to the slot 6.

The reservoir 8 is elongated and of course 65 may be of any desired size and contain any amount of sand preferred or necessary. The bottom 9 of the tank 8 is curved throughout its entire length, it being noted that the center of the bottom 9 is highest although the 70 bottom extends downwardly toward its end, having flat end portions 10. These end portions 10 are provided with openings 11 formed therethrough as shown in Fig. 3, for purposes to be hereinafter set forth. The 75 top 12 is substantially round, as shown in Fig. 1. The neck 13 extends from the top 12 and projects through the flooring 5 of the vehicle, whereby the reservoir may be filled through this neck. A closure cap 14 is re- 80 movably carried by the neck 13 and it is obvious that if desired, the cap may be removed for allowing the tank to be filled, although under ordinary conditions, the cap is carried by the neck, as shown in Figs. 1, 85 2 and 3. The retaining straps 15 extend around the tank and have flat portions 16 conforming to the shape of the bottom 9 of the reservoir and it will further be noted that these straps 15 have outwardly extending feet 17 which are secured in any desired manner to the flooring 5 of the vehicle, thus supporting the reservoir in a set position.

Guide tracks 18 are secured upon the outer surface of the end portions 10 of the 95 bottom 9 and it will be noted that the guide tracks 18 are substantially L-shape in cross section and are parallel to each other. A slide plate 19 is carried by each pair of guide tracks and these slide plates are movably supported. The slide plates 19 are provided with different sized openings 20 formed therethrough, as shown in Fig. 4, whereby the amount of sand to be dispensed may be regulated.

In order to urge the plates 19 in one direction, brackets 21 are mounted upon the flooring 5 and extend downwardly to have their lower ends in alinement with the slide plates 19. Coiled springs 22 are connected to the 100 105 110

brackets 21 and are also connected through openings 23 to the rear end of the slide plates 19. It is therefore obvious that the resiliency of the coiled springs 22 will cause the plates to move rearwardly and thus move the openings 20 out of alignment with the openings 11 formed in the end portions 10 of the bottom 9 of the reservoir 8.

A box 24 is fixed upon each pair of guide straps 18, as shown in Fig. 3 and these boxes 24 have openings 25 in their top portions, whereby the sand may pass into the box. The dispensing tubes 26 are fixedly carried by the lower portions of the boxes 24 and are 15 curved to extend to a point adjacent the peripheries of the rear wheels as shown in Fig. 1. It is therefore obvious that as sand passes through the boxes 24, it will pass through the tubes 26 and be finally dispensed 20 in the path of movement of the rear wheels.

The rods 27 are connected to the forward end of the slide plates 19 by having eyes 28 extending through openings 29 formed in the forward ends of these plates. These rods 25 27 converge forwardly and are permanently secured in any desired manner to a central plate 30. A rod 31 is connected to the forward portions of the plate 30 and this rod 31 has a coupling sleeve 32 screwed into engagement therewith. The foot lever 33 is 30 pivotally mounted upon the bracket and the coupling sleeve 32 is pivotally mounted as indicated at 34 upon this foot lever. The foot lever extends through the slot 6 formed 35 in the flooring 5 and it will be noted that the lever also extends through the floor plate 35 which is carried contiguous to the slot 6. This floor plate 35 is provided with notches 36 so that in the event a continued flow of 40 sand is desired, the lever may engage a selected notch 36 which will correspond to the openings 20 formed in the slide plates 19 and thus the desired quantity of sand will be dispensed.

45 In anti-skid devices now generally used, the structures are secured over tires. Therefore, as is well known, these anti-skid structures wear the tires out very quickly and for this reason are injurious to the same. However, the present invention does not unduly 50 wear upon the tires but merely provides a surface over which the tire may pass, which will prevent slipping or skidding of the tires and the present invention will be as ready for use during warm weather, when 55 the pavements are wet and for this reason are slippery, as during the winter when the same are slippery due to ice or snow.

When it is desired to dispense sand in 60 front of the wheels, the operator engages the foot lever 33 and shifts the same forwardly. The forward shifting of this lever draws upon the rod 31, the plate 30 and the rods 27. As the rods 27 are pulled forwardly, 65 they will also shift the slide plates 19 for-

wardly within the guide tracks 18. When a desired set of openings register with the openings 11 in the end portion 10 it is obvious the sand will pass from the reservoir through the tubes to be dispensed in the path 70 of movement of the driving wheels. When the lever is engaged with a selected notch in the plate 35, it is obvious the flow of sand will continue until the lever is released. When pressure upon the lever is released, 75 the tension of the coil springs 32 will draw the plates to their normal positions, thus moving the openings 20 out of registry with the openings 11 in the end portions 10 of the bottom 9 of the reservoir 8. Rearward 80 movement of these plates also moves the rods 27 rearwardly and also moves the plate 30 and rod 31 rearwardly, whereby the operating rod will be moved to its normal position, as indicated in Fig. 1. As above suggested, 85 the device will be in condition for instant use at any time and under any conditions and the sand may be allowed to flow as long as desired. It will be noted that the concaved construction of the bottom 9 of this 90 tank 8 causes the sand in this reservoir to move toward the ends of the reservoir.

The foregoing description and the drawings have reference to what may be considered the preferred, or approved, form of my 95 invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. In a device of the class described, the 10 combination of a support, a reservoir carried by said support and having an opening, a slide plate connected to said reservoir and having various sized openings formed there-through, an operating lever movably mounted upon said support, means connecting said operating lever to said slide plate, whereby as said lever is moved said plate will be shifted, and means associated with said lever for indicating proper movement 11 of said lever to bring a desired opening of said plate into registry with the opening of said reservoir, and said last mentioned means being adapted to releasably hold said lever in a set position.

2. In a device of the class described, the 1 combination of a support, a reservoir carried by said support, and having an opening, a slide plate mounted upon said reservoir, said plate having various sized openings, a lever 1 pivotally mounted upon said support, means connecting said lever to said slide plate, whereby as said lever is moved, said slide plate will be shifted, a plate carried by said support and having notches formed therein

to correspond with the openings formed in said first mentioned plate, whereby said lever may be moved to a desired notch for bringing the desired opening of said plate 5 into registry with the opening of said reservoir, and said lever being adapted to be received by the selected notch, to be held against accidental movement.

3. In a device of the character described, 10 the combination of a reservoir, having a curved bottom which extends downwardly toward its ends and terminates in flat end portions provided with openings, guide tracks carried by said flat end portions adjacent said openings, perforated slide plates

carried by said tracks, boxes fixed upon said tracks and having openings formed therein, dispensing tubes connected to said boxes, whereby as said slide plates are moved, the contents of the reservoir may pass through 20 the openings in the flat end portions and said slide plates into said boxes to be finally dispensed through said tubes.

In testimony whereof I affix my signature in presence of two witnesses.

RAYMOND ARMSTRONG.
